UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, ENGLAND.

LOADING APPARATUS OF HEAVY GUNS.

1,094,130.

Specification of Letters Patent. Patented Apr. 21, 1914.

Application filed October 4, 1911. Serial No. 652,689.

To all whom it may concern:

Be it known that we, ARTHUR TREVOR DAWSON, knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in or Relating to the Loading Apparatus of Heavy Guns, of which the following is a specification.

This invention relates to the loading apparatus of heavy guns, and has particular reference to the means controlling the movements of the rammer.

According to our invention we provide means whereby the loading cage is capable of causing the rammer motor to automatically effect the ramming of the projectile into the gun, as the said cage reaches the gun loading position. The rammer motor may be controlled by a device which is under the influence of the gun loading cage so that as the cage completes its ascent the said device is automatically moved into a position to cause the motor to effect the outward or ramming stroke of the rammer.

In order that the said invention may be clearly understood and readily carried into effect we will describe the same more fully with reference to the accompanying drawings, in which:

Figure 1 is a diagrammatic side elevation of a gun provided with our improvements, and Fig. 2 is an enlarged view of the rammer controlling device which is under the influence of the loading cage.

A is the gun, B the slide frame, B' the loading arm, C the loading cage, D the rammer, D' the rammer control hand lever and D² the hand control valve connected to the said lever.

The device for controlling the rammer motor comprises in the example shown a valve D^x carried by the loading arm B'. The said valve is in the form of a differential hydraulic ram having a piston d^o formed thereon working in a cylinder which is connected by means of a pipe d' with the hand control valve D² mounted on the gun platform. The stem d of the valve D^x projects beyond the valve casing D^{xx} and is normally

engaged by a spring controlled bolt D³ to lock the said valve in the position shown in Fig. 2. By this means the rammer (which is shown by way of example as of the flexible chain type) is retained in the withdrawn position by the valve D^x admitting pressure fluid from the pipe d^x through the pipe d^{2x} to the motor F of the rammer, the said motor thereby continually exerting power on the rammer to retain the head thereof against the frame or structure by which it is supported. The said spring controlled bolt D³ is connected to a pivoted lever d² the end d³ of which lies in the path of a projection A' on the gun loading cage C, so that when the said cage reaches its loading position the said lever d² is displaced to withdraw the spring controlled bolt D³ from engagement with the valve stem d. The hand lever D' having been placed to the "ram" position prior to the ascent of the gun loading cage the hand control valve D² is in a position to place the pipe d' to exhaust, and the preponderating pressure on the end of the piston d^o of the valve D^x is therefore removed, and the said valve, under the influence of the pressure fluid supplied by the pipe d^x, then moves to the right (when the bolt D³ is withdrawn) and admits pressure fluid through the pipe d^{2x} to the motor to cause the rammer to ram the projectile into the gun. After the projectile has been rammed the hand lever D' is moved to a position to cause the rammer to perform its withdrawing stroke, and by subsequently operating the said hand lever D' the ramming of the powder charges can be effected, this ramming stroke being automatically reversed through mechanism comprising a locking bolt D⁵, a reversing cylinder E^x and a cut-off valve D^o operated by the rammer; this arrangement is fully set forth in the specification of our British Patent No. 20,119 of 1910.

When the rammer lever D' is brought back to its "withdraw" position, the valve D² is moved to its original position in which the said valve is supplying pressure fluid through the pipe d' to the piston d^o of the valve D^x. The preponderance of pressure on the said piston then moves the said valve toward the left so that it is admitting pressure fluid to the rammer motor to cause the

rammer to perform its withdrawing stroke. The valve D^x is in this position when the rammer has been withdrawn after ramming the last of the powder charges and when the loading cage A is lowered the spring controlled bolt D^x is caused to engage with the valve stem d and the valve D^x is thus locked in the "withdraw" position.

What we claim and desire to secure by Letters Patent of the United States is:—

1. In gun loading apparatus, the combination with the loading cage, the rammer and its motor, of means for controlling said motor, a device coöperating with said means, and means for automatically operating said device as the cage reaches its loading position.

2. In gun loading apparatus, the combination with the loading cage, the rammer and its hydraulic motor, of a valve for controlling the said motor, a device coöperating with said valve, and means for automatically operating said device as the cage reaches its loading position.

3. In gun loading apparatus, the combination with the loading cage, the rammer and its hydraulic motor, of a valve for controlling the said motor, and a spring bolt under the control of the loading cage for automatically permitting said valve to move as the cage reaches its loading position.

4. In gun loading apparatus, the combination with the loading cage, the rammer and its hydraulic motor, a hydraulic valve for controlling the said motor, a device for normally retaining said valve in the position to keep the rammer withdrawn and means on the loading cage for operating the said device to release the valve.

5. In gun loading apparatus, the combination with the loading cage, the rammer and its hydraulic motor, of a differential hydraulic valve for controlling the said motor, a pipe supplying pressure fluid to said valve, a device for normally retaining said valve in the position to keep the rammer withdrawn

and means on the loading cage for operating said device to release the valve.

6. In gun loading apparatus, the combination with the loading cage, the rammer and its hydraulic motor, of a differential hydraulic valve for controlling the said motor, a pipe supplying pressure fluid to said valve, a spring controlled bolt normally engaging with the said valve and means on the loading cage for lifting said bolt out of engagement with the valve.

7. In gun loading apparatus, the combination with the loading cage, the rammer and its hydraulic motor, of a differential hydraulic valve for controlling the said motor, a pipe supplying pressure fluid to said valve, a spring controlled bolt normally engaging with the said valve, a lever connected to said bolt, and a projection on the cage for coöperating with said lever to lift the bolt.

8. In gun loading apparatus, the combination with the loading cage, the rammer, its hydraulic motor and its hand control valve, of a differential hydraulic valve directly controlling the motor, a pipe supplying pressure fluid to said differential valve, a ram forming part of said valve, a cylinder in which said ram is disposed, a pipe connecting said cylinder to the hand control valve, a spring controlled bolt normally engaging with said differential valve, a lever connected to said bolt, and a projection on the cage for coöperating with said lever to lift the bolt.

In testimony whereof we affix our signatures in presence of two witnesses.

ARTHUR TREVOR DAWSON.
JAMES HORNE.
